CONTAINER FOR SEEDLINGS AND CUTTINGS

Archibald John Hundt, Castle Hill, New South Wales,
Australia, assignor to Walter Barr Pty. Limited, Enfield,
New South Wales, Australia, a corporation of New South Wales

Filed Feb. 19, 1968, Ser. No. 10,635

Term of patent 3½ years

(Cl. D35—3)

FIG. 3

FIG. 1 is a perspective view from above of a container for seedlings and cuttings, according to my design, the container being in closed condition,

FIG. 2 is a perspective view from below of the container in FIG. 1; and

FIG. 3 is a perspective view from above of the container in FIG. 1 in opened condition.

I claim:

The ornamental design for a container for seedlings and cuttings, substantially as shown and described.
